UNITED STATES PATENT OFFICE.

IRA L. MOORE, OF SPRINGVALE, MAINE.

STEAM-BOILER.

1,244,067.

Specification of Letters Patent. Patented Oct. 23, 1917.

Application filed May 31, 1916. Serial No. 100,944.

To all whom it may concern:

Be it known that I, IRA L. MOORE, a subject of the King of Great Britain, residing at Springvale, in the county of York and 5 State of Maine, have invented certain new and useful Improvements in Steam-Boilers; and I do hereby declare the following to be a full, clear, and exact description of the invention, such as will enable others skilled 10 in the art to which it appertains to make and use the same.

The primary object of this invention is to provide a novel type of steam boiler for use in heating dwellings, and of such construction that the same can be manufactured 15 cheaply and easily installed.

Another object of the invention is to provide a boiler, of this nature, so constructed that steam can be generated in a very short 20 period.

A further object of the invention is the provision of a steam boiler, designed to be heated by liquid or gaseous fuel, and which boiler is provided with passages therein for 25 the circulation of the heat from the burner.

Other objects will appear and be better understood from that embodiment of my invention of which the following is a specification, reference being had to the accompanying drawings forming a part thereof, 30 in which:

Figure 1 is a vertical sectional view of the boiler and the heater therefor.

Fig. 2 is a top plan view thereof, and

Fig. 3 is a section taken on the line 3—3 of Fig. 1.

Referring to the drawings in detail, the boiler is shown as comprising an outer casing or shell 1 and a pair of spaced inner bodies 40 or shells designated, respectively, by the numerals 2 and 3. The inner bodies or shells 2 and 3 have their upper ends terminating in the same plane and disposed below and in spaced relation with the upper end of the casing 1, and each is formed of an outer cylindrical wall 4 and an inner inverted frusto-conical shaped wall 5, the outer wall 4 of the body 2 being arranged in spaced relation with the inner surface of the body 50 1. Each body or shell has the upper ends of the walls 4 and 5 connected by a web, the webs connecting the respective walls 4 and 5 being designated by the numeral 6 and serve as closures for the upper ends 55 of the spaces between the outer and inner walls 4 and 5 of each of the bodies 2 and 3.

The lower end of the casing 1 and the wall 4 of the inner body 2 are connected by means of a web 7, and the lower end of the inner wall 5 of the body 2 and the lower end of the outer wall 4 of the body or shell 3, terminate above the lower end of the outer wall 4 of the body 2 and above the lower end of the casing 1, and are connected by means of a web 8. 60 65

A conical shaped tube 9 extends through the body or shell 3, and the lower end of the inner wall 5 of the shell 3 and the lower end of the tube 9 lie above the lower end of the outer wall 4 of the shell 3 and are 70 connected by means of a web 10.

The upper end of the casing 1 is formed to provide a steam dome 11, and passing centrally through the dome 11 is the upper end 12 of the tube 9. A pair of steam outlet pipes 13 and 14 are arranged, respectively, on opposite sides of the upper end 12 of the tube 9 and arranged in communication with the interior of the dome 11, and the said pipe is designed to be connected with suitable pipes, not shown, that communicate with different radiators in the building. 75 80

Vertically disposed tubes 15, of arcuate shape in cross section, are arranged within the dome 11 and have their lower ends communicating with the spaces between the inner and outer walls of the respective bodies 2 and 3, by means of openings 16 formed in the connecting webs 6, and the upper ends 90 of the tubes 15 communicate with openings 17 formed in the upper wall of the dome 11. 85

The space between the casing 1 and the outer wall of the inner body 2 and the space between the inner wall of the body 2 and 95 the outer wall of the body 3, provide water chambers designated, respectively, by the numerals 18 and 19, and are connected at their lower ends at a diametrically opposite point by means of tubes or pipes 20, which 100 extend across the lower end of the space between the outer and inner walls of the body 2. Likewise the space between the inner wall 5 and the tube 9 provides a water chamber 21, which has connection with the chamber between the bodies 2 and 3 by means of connecting tubes 22, which are arranged at diametrically opposite points and above the tubes 18. The spaces between the inner and outer walls of the respective bodies 2 and 3 are opened, at the lower ends, likewise the lower end of the tube 9, is opened, 105 110

and a suitable liquid or gaseous fuel burner, not shown, is to be positioned below the boiler and the heat emitting from the same will pass upwardly through the tube 9 and through the spaces between the outer and inner walls 4 and 5 of each of the bodies 2 and 3 and heat the water in the water chambers 18, 19 and 21 and thence pass out through the upper end 12 of the tube 9 and 16 through the pipes 15.

The water chambers in the boiler are of unequal depth and are to be supplied with water from a feeder 23. This feeder includes a body which has an inlet pipe 24 15 extending through one side thereof and has the inner end thereof arranged in communication with a vertically disposed hollow body 25, the upper end of which is normally closed by means of an inwardly movable 20 valve 26. The valve 26 has a stem 27 formed thereon, which projects through the body 19 and is connected to the arm of a float 28, the said arm of the float being pivoted to the wall of the feeder 23, as shown at 29. 25 The pipe 24 is connected with a suitable water supply, not shown, which may be either a tank or a water main.

A pipe 30 communicates the lower end of the feeder 23 with the lower end of the 30 water chamber 18, and that end of the pipe 30, which is connected to the feeder 23 is closed by means of a screen 31. A check valve 32 is located within the pipe 30 and serves to prevent back flow of the water 35 from the boiler.

A pipe 33 communicates the upper end of the feeder 23 with the dome 11 and admits of steam from the dome passing into the upper end of the feeder 23, so as to 40 equalize the pressure within the boiler, and the feeder, and assist in the flow of water through the pipe 24. A check valve 34 is located within the pipe 33 and is adapted to be opened by the pressure of steam in the 45 dome and to prevent the return of steam from the feeder to the dome.

In use, water is permitted to flow from the feeder to the water chambers in the boiler. The burner, to be used, is lighted and the 50 heat from the same passes up through the air passages in the boiler and will heat the water so as to generate steam in the dome 11. Some of the steam generated will pass through the pipe 33, and as soon as the pressure 55 therein is sufficient to unseat the valve 34 the steam will enter the feeder 23 and assist the flow of water through the pipe 30 to the boiler. When the water level, in the feeder, lowers, the float 28 will descend and 60 open the valve 26, so as to admit of the water passing from the body 25 to the feeder, so that the desired level is again reached.

The boiler is provided with a water gage 65 and the lower end of the feeder 23 is provided with a discharge cock 36, by means

of which the feeder can be drained when it is desired to clean the feeder.

The check valve 32 is pivoted, at a point below the upper end thereof, to the lower end of a depending and curved bracket 37. 70 A set screw 38 is adjustably mounted through the upper side of the pipe 30 and extends diagonally and is adjustable against the upper end of the check valve 32. When it is desired to empty the feeder 23 and the 75 boiler so as to admit of the interiors thereof to be cleaned, the discharge cock is opened and the set screw 38 is adjusted against the upper end of the check valve 32, so as to raise the valve to establish communication 80 between the feeder and the boiler, to admit of the water in the boiler discharging into the feeder and out through the discharge cock 36.

It will, of course, be understood that no 85 limitation is to be placed on the number of inner shells or bodies to be fitted within the outer body 1, for, if desired, only one may be employed, or if deemed necessary three 90 or more.

Having thus described my invention what I claim as new, is:

1. The combination with a boiler having a steam dome and a feeder for the boiler, of a pipe establishing communication between 95 the lower end of the feeder and the boiler, a check valve within the pipe, a screw adjustable through the pipe and against the check valve, a second pipe establishing communication between the upper end of the feeder 100 and the dome of the boiler, and a check valve positioned within the last-mentioned pipe, for the purpose specified.

2. A boiler of the class described comprising a casing, a pair of annular bodies located within the casing and disposed in concentric relation and having their upper ends spaced from the upper end of the casing to define a steam dome, each of the annular bodies consisting of a substantially 110 frusto-conical shaped outer wall and an inverted substantially frusto-conical shaped inner wall spaced from the outer wall so as to provide a flue restricted toward its upper end, the outer wall of the outermost 115 annular body being spaced from the inner surface of the casing, and the outer wall of the innermost annular body being spaced from the inner wall of the outermost annular body so as to provide water chambers 120 which are restricted toward their lower ends, a web connecting the lower end of the outer wall of the outermost annular body to the lower end of the wall of the casing, a web connecting the lower end of the outer 125 wall of the innermost annular body to the lower end of the inner wall of the outermost annular body, a web connecting the upper ends of the inner and outer walls of each annular body to each other and pro- 130

vided with openings, tubes establishing communication between the water chambers, tubes extending through the steam dome and of arcuate shape in cross section and 5 having communication with the openings in the connecting webs for the upper ends of the walls of the respective inner bodies, a tube extending through the innermost annular body and spaced therefrom and decreasing in diameter from the lower end 10

thereof to the upper end, and a web connecting the lower end of the wall of the last-mentioned tube to the lower end of the wall of the innermost annular body.

In testimony whereof I affix my signature 15 in presence of two witnesses.

IRA L. MOORE.
